UNITED STATES PATENT OFFICE.

GEORGE DELOS HOFFMAN, OF NEW YORK, N. Y., ASSIGNOR TO NORWALL MANUFACTURING COMPANY, OF CHICAGO, ILLINOIS, A CORPORATION OF ILLINOIS.

AUTOMATIC AIR-VALVE.

No. 899,110.

Specification of Letters Patent.

Patented Sept. 22, 1908.

Application filed August 30, 1907. Serial No. 390,727.

To all whom it may concern:

Be it known that I, GEORGE DELOS HOFFMAN, a citizen of the United States of America, residing temporarily in the borough of 5 Manhattan, city and State of New York, United States of America, have invented a new and useful Automatic Air-Valve; and I do hereby declare the following to be a full, clear, and exact description of the same.

- 10 The present improvements relate to automatic air valves (especially those applied to steam radiators) wherein water, due to condensing of steam, is used to operate a float carrying a valve, and wherein the differences 15 in temperature of the air or steam in a radiator, cause expansion and contraction of air in an air-chamber for the purpose of raising and lowering the level of the water in the float-chamber.
- 20 The object of the invention is to provide such an automatic air valve with an improved form of siphon, in order to remove surplus water from the float-chamber and to lead such surplus to the radiator, and with 25 means additional to and separate from the siphon, which is of great value in the operation of the device.

In the accompanying drawings, Figure 1 indicates a vertical section on line 1—1 of 30 Fig. 2, through one form of automatic air valve embodying my present improvements; Fig. 2 is a cross-section, on the line 2—2 of Fig. 1, and Fig. 3 is a vertical section on the line 3—3 of Fig. 2.

- 35 The device shown comprises essentially an outer casing, an inner casing, a top provided with a valve and a bottom, a drainage chamber within said outer casing and a siphon in the inner casing and in the drainage chamber, 40 a radiator-nipple, and a separate pipe in said drainage-chamber and leading towards the nipple.

A indicates the outer casing, cylindrical in shape, and B indicates the inner casing, concentric with that first named and provided with a longitudinal depression or rib. Between the two mentioned casings, a ring-like air-chamber, a is provided, which is interrupted, as hereinafter described, by a drainage-chamber. The inner casing B comprises 50 and provides a float-chamber b, and the air-chamber is connected as usual with the float-chamber, near its bottom, by an opening b' in the casing B. A bottom and a top, of usual construction, are provided, the latter having

a port Y, which is closed, or opened to the desired extent, by a valve carried upon the upper end of a float C in the float-chamber. This latter chamber, near its top, also communicates, by an opening D, in the upper 60 part or end of the longitudinal depression or rib, with the upper end of a drainage-chamber E, of sheet metal bent to shape to form a narrow casing, the length of which substantially equals the space between the inner and outer casings and which, while it includes the depression or rib aforesaid, is entirely included in and closed from the air-chamber. At its lower end, the drainage-chamber E opens into and constitutes a continuation of 70 the opening through a radiator-nipple G, extending outwardly from the outer casing near the lower end of the device, and the exterior of which nipple is threaded for screw engagement with a radiator. The air chamber a is entirely shut off from the nipple G.

A cap X, mainly ornamental, is screwed to the upper end of the device, and is provided with an opening x for the escape of air and steam.

Within the drainage-chamber E, I house one end (the longer leg) of a siphon F, the inner or shorter end of which, after passing through the opening D, depends into the depression or rib of the float-chamber to a 85 point (about) midway of the length thereof, while the outer end or leg of such siphon leads towards and its outer end, f, preferably stops short of and does not enter the opening through the radiator-nipple.

In practice, I have found that a siphon, even when complete, does not, when used alone, (and especially when inclined towards or aligned with the opening of the radiator-nipple) always give satisfactory results for 95 the purpose of removing surplus water from the float-chamber. In a companion application, Serial No. 390728 filed Aug. 30, 1907, I have shown the employment, of a pipe additional to, constituting a continuation of and 100 having a swiveling connection with the siphon.

The present invention contemplates the employment of a pipe, H, separate from and not a continuation of the siphon F. Said 105 pipe is housed and firmly secured within the drainage-chamber E, and is bent so as to have its lower open end h co-axial with and at the upper part of the opening of the radiator-nipple without (preferably) projecting 110

from said nipple, while the upper open end h' of said pipe stops short of but level (preferably) with the opening D.

The addition of pipe H, especially when bent as shown (in conjunction with a siphon the outer leg whereof stops short of the nipple) is highly important, as the steam and air entering from the radiator apparently tend to pass upwardly through the pipe to be delivered to opening D, and this result balances the pressure between the radiator and the inner chamber b , and thus permits a freer discharge from said siphon.

Upon first use of the device, steam enters (from the radiator) through nipple G, and, after passing upwardly through drainage-chamber E, and through pipe H therein, enters the float-chamber b and escapes through port Y. The condensation of steam in the float-chamber soon produces enough water therein to raise the float C and cut off the escape of steam through port Y. The heating of the air-chamber a , during the operation aforesaid, has rarefied the air in that chamber and caused escape of some air through opening b' and by way of port Y. Upon a subsequent cooling of the device, the contraction of the air in chamber a draws water thereinto from the float-chamber, and the float descends and again opens port Y, again permitting escape of steam, a consequent re-heating of the air-chamber, an expansion of air therein, and transfer of water therefrom to the float-chamber and the lifting of the float and seating of the carried valve.

It frequently happens that a radiator, while venting, discharges water and, under this condition, the water surges against the air - valve. In ordinary float - valves, the valve attached to the float closes a port (as Y), and the valve remains closed and the radiator partially cold. With my construction, however, the valve, while freely venting the air from the radiator, closes against water (as with ordinary valves) and remains closed as long as water remains against the valve; but the instant the water in the radiator falls away from the valve, the siphon automatically discharges the water (from chamber b) back to the radiator, and the valve re-commences venting. No matter how frequently water may come to the valve, the latter will instantly close tightly against leakage therethrough; and the instant the water falls in the radiator, the siphon always automatically begins its work.

What I claim is:

1. In an automatic air-valve, a casing comprising a float-chamber and an air-cham-

ber connected with the lower part of said float-chamber, a drainage-chamber connected at its upper end with the float-chamber, a radiator-nipple extending outwardly from the drainage-chamber, and a siphon, having its inner leg in the float-chamber and leading therefrom, and with its outer leg within the drainage-chamber and stopping short of the opening through said nipple.

2. In an automatic air-valve, a casing comprising a float-chamber and an air-chamber connected with the lower part of said float-chamber, a drainage-chamber entirely closed from the air-chamber and connected at its upper end with the float-chamber, a radiator-nipple extending outwardly from the drainage-chamber, a siphon leading from the float-chamber aforesaid and with its outer leg in the drainage-chamber and stopping short of the opening through said nipple, and a separate pipe extending downwardly within said drainage-chamber and with its lower end extending outwardly and within the opening of said nipple.

3. In an automatic air-valve, a casing comprising a float-chamber and an air-chamber connected with the lower part of said float-chamber, a drainage-chamber entirely closed from the air-chamber and connected at its upper end with said float-chamber, a radiator-nipple extending outwardly from said drainage-chamber, a siphon having its inner leg depending into the float-chamber, and with its outer leg in the drainage-chamber leading towards and stopping short of the opening through the nipple, and a separate pipe having its lower end outwardly extending within said nipple-opening and said pipe leading upwardly within the drainage-chamber towards and stopping short of the connection with the float-chamber.

4. In an automatic air-valve, a casing comprising a float-chamber, a drainage-chamber, a radiator-nipple leading to the drainage-chamber and extending from the outside of said casing, an air-chamber connected with said float-chamber, and closed from said nipple, a siphon having its inner leg within the float-chamber for discharging into the drainage-chamber towards the opening of said nipple, and a separate pipe connected with the float-chamber above the inner leg of the siphon.

In testimony whereof, I have signed my name to this specification in the presence of two subscribing witnesses.

GEORGE DELOS HOFFMAN.
